UNITED STATES PATENT OFFICE.

EDWARD L. PEMBERTON, OF NEW HAVEN, CONNECTICUT, ASSIGNOR TO EDGAR ALLEN
AMERICAN MANGANESE STEEL COMPANY, OF AUGUSTA, MAINE, A CORPORATION
OF MAINE.

ADJUSTABLE CRUSHER-HEAD FOR ROCK-CRUSHERS.

1,035,041.

Specification of Letters Patent. Patented Aug. 6, 1912.

Application filed February 13, 1912. Serial No. 677,310.

To all whom it may concern:

Be it known that I, EDWARD L. PEMBERTON, a citizen of the United States, and a resident of New Haven, in the county of New Haven and State of Connecticut, have made and invented certain new and useful Improvements in Adjustable Crusher-Heads for Rock-Crushers, of which the following is a specification.

10 My invention relates to crusher heads for gyratory crushing mills designed for crushing stone, ore, and similar hard substances; and more particularly to that type of crusher head in which a supporting core or center is secured to or formed integrally with a shaft whereby the head is operated and to which core a surrounding mantle is secured, so that the mantle may be removed from the core when it has become worn in 15 use and replaced by a new mantle.

The surrounding shell or mantle of crusher heads of the type above referred to is commonly formed from cast manganese steel in order to provide excessive hardness 25 and toughness for the same. A mantle made of this material, however, becomes stretched in use and loose upon the supporting core, because the material of which it is made while exceedingly hard and tough, is nevertheless quite ductile, from which it follows 30 that in practical use the mantle will need to be frequently adjusted in order to maintain a tight fit between it and the supporting core.

35 The supporting core or center of crusher heads of the type above referred to is commonly made conical and placed with the small end upward when in use, and, as the mantle is also conical in form, it follows that 40 looseness between the core and mantle resulting from stretching of the mantle when in use is most readily compensated for by moving the mantle downward upon the supporting core; and the object of my invention 45 is to provide improved means for moving the mantle longitudinally of the supporting core and for securing it in position after it has been adjusted to secure a tight fit between the core and mantle.

50 A further object of my invention is to provide a crusher head having a surrounding mantle adjustable longitudinally thereupon, and which head may be easily and readily manufactured, which will be simple

in construction and effective for the purposes for which it is designed. 55

With the above and other objects of invention in view, my invention consists in the improved crusher head and means for adjusting the mantle thereof longitudinally 60 upon its supporting core hereinafter described and claimed, and in such variations and modifications thereof as will be obvious to those skilled in the art to which my invention relates. 65

In the accompanying drawing wherein the preferred embodiment of my invention is illustrated; Figure 1 is a view showing a section of my improved crusher head upon a vertical central plane, the shaft through 70 which the head is driven being shown in elevation; Fig. 2 is a view showing a section of the mantle only upon a central vertical plane at right angles to the plane of Fig. 1, this view showing the internal features of 75 the mantle; Fig. 3 is a view showing a supporting core or center formed integrally with the driving shaft, and not separable therefrom as in Fig. 1; Fig. 4 is a fragmentary view showing a portion of the upper 80 end of a slightly modified form of my improved crusher head; Fig. 5 is a view showing the upper end of the mantle in plan; Fig. 6 is a view showing my improved 85 crusher head as seen from a position beneath it; Fig. 7 is a view showing a locking plate used in my device; Fig. 8 is a view showing a modified form of locking plate; and, Fig. 9 is a fragmentary view showing 90 a modified arrangement of an adjusting rack forming a part of my device.

Referring to the drawings, the reference numeral 10 designates the main driving shaft of a gyratory crushing mill, and 11 is a supporting core or center which serves as a support for a removable mantle 20 and which core may be formed either separately from the shaft 10 and driven therefrom by means of a suitable key, as shown in Fig. 1 or integrally with the shaft as shown in Fig. 3, the said core being secured upon the shaft, in the form shown in Fig. 1, by means of lock nuts 12 in a manner well understood by those skilled in the art. This supporting core or center is of general conical form. A 105 portion of the upper end thereof is, however, preferably made cylindrical, as shown at 13, Figs. 1 and 3, although it may be conical

throughout its entire length, as shown in Fig. 4. In either case, the periphery of the core is provided with longitudinally extending grooves 14, four of such grooves being shown in the embodiment of my invention illustrated, although the number of grooves is immaterial, and the lower ends of these grooves communicate with recesses or pockets 15 within which are located adjusting

10 screws or worms 16.

In the drawings I have illustrated two only of the grooves 14 as communicating with recesses in which adjusting screws are placed, as two such screws located upon opposite sides of the core will ordinarily be found sufficient, although it will be understood that such recesses and adjusting screws may be provided at the lower end of each of the longitudinal grooves 14 whatever may be

15 the number of such grooves used.

The adjusting screws 16 are provided with trunnions 17, 18 which rest in bearings formed in the supporting core, as best shown in Fig. 3, and the lower trunnion 18 is 20 prolonged and made square in order to receive a suitable wrench for turning the screw, and to receive locking plates 19, which, when in place, prevent the screws from turning, as will be hereinafter more

25 fully described.

The reference character 20 designates a mantle conical in form which surrounds the supporting core 11 and is adjustable longitudinally thereof and thereupon, as above 30 explained. The upper end of this mantle is provided with inwardly extending lugs 21 corresponding in number with and extending into the upper ends of the longitudinal grooves 14. Intermediate lugs 22 are 35 also provided which project from the inner surface of the mantle, and into the longitudinal grooves 14, as many of such intermediate lugs being provided along the length of the mantle as may be found necessary in order to drive the mantle, it being understood that the mantle is driven from the core or center through the lugs 21 and 22.

The inner surface of the lower end of the mantle 20 is provided with racks 23 corresponding in number with the number of adjusting screws 16 employed in a particular head, and which racks are engaged by the said screws as best shown in Fig. 1. These racks may be formed integrally with the mantle as shown in Fig. 1, as the same is cast, or the racks may be formed separate from the mantle and embedded therein as the mantle is cast, the racks in such cases being placed in the molds before the fluid metal from which the mantle is formed is poured thereinto, a rack secured in place in this way being shown at 24, Fig. 9. The lugs 22 and racks 23 are located in grooves 25 extending longitudinally of the mantle 20.

65 The lower ends of the supporting core 11

and mantle 20 are provided with registering recesses, as shown in Fig. 6, within which recesses the locking plates 19 lie, the plates being held in position by keys 26 extending through the lower trunnion 18 of the adjusting

7

Fig. 7 shows locking plates 19 as square, although it will be obvious that they may be of any form, one of hexagonal form being shown at 27, Fig. 8. The recesses in which the locking plates lie will in all cases correspond in form with the shape of the plate.

In view of the premises it will be obvious that upon removing the keys 25 and locking plates 19 from the lower trunnion of the adjusting screws, the screws may be engaged by a wrench and rotated upon their axes, whereby the mantle 20 will be moved downward upon the supporting core 11 to take up any looseness which may have developed between the mantle and core due to stretching the mantle. After the mantle has been moved downward to secure a tight fit between it and the supporting core, the locking plates 19 will be replaced and secured in position upon the trunnion 18, to thereby prevent the adjusting screws from turning when the head is in use.

8

The upper end of the mantle 20 is subjected to less wear when the head is in use 9 than the lower portions because most of the crushing is done at the lower end of the mantle, from which it follows that the upper end thereof will stretch but little, while the lower portions of the mantle will 10 stretch to a much greater extent. It therefore follows that the upper end of the core may be cylindrical, as shown at 13 without interfering with the longitudinal adjustment of the mantle upon the core; although 11 as explained above, the core may be conical throughout, in which case the upper end of the mantle will be made to fit somewhat loosely about the upper end of the supporting core.

11

Having thus described and explained my invention, I claim and desire to secure by Letters Patent:

1. In a crusher head, a conical supporting core; a conical mantle surrounding said core and adjustable longitudinally thereupon; a worm carried by one of said members; a rack carried by the other of said members and with which said worm engages; and means whereby said mantle is driven from 12 said core.

11

2. In a crusher head, a conical supporting core; a conical mantle surrounding said core and adjustable longitudinally thereupon; a worm carried by one of said members; a rack carried by the other of said members and with which said worm engages; a groove extending longitudinally of one of said members and terminating at one end thereof; and a lug upon the other of 13

12

said members and which lug projects into said groove.

3. In a crusher head, a conical supporting core; a conical mantle surrounding said core and adjustable longitudinally thereupon; a groove extending longitudinally of one of said members and terminating at one end thereof; a lug upon the other of said members and which lug projects into said groove; and means including a rack carried by one of said members and a worm carried by the other member and in engagement with said rack for adjusting said mantle longitudinally upon said core.

15 4. In a crusher head, a conical supporting core having a longitudinally extending groove upon its periphery and the lower end of which groove is enlarged to form a recess or pocket; a conical mantle surrounding said core and adjustable longitudinally thereupon, said mantle having a lug upon its inner surface which projects into the groove aforesaid upon said core; a worm located within the recess or pocket aforesaid; and a rack carried by said mantle and with which said worm engages.

5. In a crusher head, a conical supporting core having a longitudinally extending groove upon its periphery and the lower end of which groove is enlarged to form a recess or pocket; a conical mantle surrounding said core and adjustable longitudinally thereupon, said mantle having a lug upon its inner surface which projects into the groove aforesaid upon said core; a worm located

within the recess or pocket aforesaid and having supporting trunnions supported in bearings formed in said core and through one of which trunnions said worm may be operated; a rack carried by said mantle and with which said worm engages; and a locking plate located within a recess formed in the lower end of the crusher head and in locking engagement with the trunnion through which the worm is operated.

40 45 6. In a crusher head, a conical supporting core having a longitudinally extending groove upon its periphery and the lower end of which groove is enlarged to form a recess or pocket; a conical mantle surrounding said core and adjustable longitudinally thereupon, said mantle having a lug upon its inner surface which projects into the groove aforesaid upon said core; a worm located within the recess or pocket aforesaid and having supporting trunnions supported in bearings formed in said core and through one of which trunnions said worm may be operated; a rack carried by said mantle and with which said worm engages; and means 50 55 60 for locking said worm against rotation upon said trunnions.

Signed at New York, Manhattan, in the county of New York and State of New York this 10th day of February, A. D. 1912.

EDWARD L. PEMBERTON.
